UNITED STATES PATENT OFFICE.

ALONZO F. GAIDOS AND FRANK H. GUY, OF RACINE, WISCONSIN.

STREET OR STATION INDICATOR.

1,365,905.

Specification of Letters Patent. Patented Jan. 18, 1921.

Application filed August 23, 1919. Serial No. 319,435.

To all whom it may concern:

Be it known that we, ALONZO F. GAIDOS and FRANK H. GUY, citizens of the United States, and residents of Racine, in the county of Racine and State of Wisconsin, have invented certain new and useful Improvements in Street or Station Indicators; and we do hereby declare that the following is a full, clear, and exact description thereof.

10 Our invention relates to new and useful improvements in street or station indicators for use on railway vehicles to successively indicate and display the names of the various stopping points in the route of the vehicle, the present device being more particularly of that type including a pair of rollers adapted to receive a flexible web or ribbon containing the names of the various streets and stations and having means for imparting successive step movements to the ribbon or web whereby to successively display the names at a suitable sight opening during the travel of the vehicle.

15 It is in general the object of our invention to simplify and otherwise improve the structure and to increase the efficiency and reliability of operation of devices of this character.

20 It is more particularly our object to provide an arrangement for insuring positive and accurate step movements of the name bearing ribbon and for insuring proper winding of the ribbon on its spools in a manner compensating in the varying diameters of the peripheries of the ribbon rolls incidental to winding and unwinding the ribbon.

25 A further object resides in the provision of an arrangement whereby the name bearing ribbon may be most readily removed and replaced to facilitate adaptation of the indicating device for use on various routes by the substitution of ribbons having the differing sets of names for the routes.

30 35 40 45 It is still further our object to provide an arrangement including a casing wherein the name bearing ribbon and its operating mechanism may be disposed compactly and in such manner that the ribbon may be viewed from both sides of the casing, so that the casing may be disposed in the center of the railway car or other vehicle.

50 55 With the above and other objects and advantages in view, which will be apparent as the description proceeds, our invention resides in the novel features of construction,

combination and arrangement of the parts as hereinafter described and defined by the appended claims.

In the accompanying drawings:

Fig. 1 is a front elevational view of an indicator mechanism embodying our invention, the door of the casing being removed and the central portion of the mechanism being broken away. 60

Fig. 2 is a smaller front elevational view of the device with the door of the casing in place. 65

Fig. 3 is a detailed sectional view of the pawl for procuring step movement of the name bearing ribbon. 70

Fig. 4 is a sectional view through the casing on a plane indicated by the line 4—4 of Fig. 1. 75

Fig. 5 is a vertical sectional view through the casing on a plane indicated by the line 5—5 of Fig. 1.

Fig. 6 is a detailed sectional view similar to Fig. 4, but showing a modified structure for procuring an increased step movement 80 of the name bearing ribbon in proportion to the primary impulse.

Fig. 7 is a view similar to Fig. 4, but showing another modification. 85

Fig. 8 is a detail section view showing the clutch connection of one of the pulleys for winding the name bearing ribbon.

Referring now more particularly to the drawings, we provide a casing including top, bottom and end walls 5, 6 and 7 respectively, a rigid side wall 8 and a side wall 9 which is hinged to the top wall 5 to provide a door for the casing. Vertical bearing brackets 10 are provided in the end portions of the casing and upper and lower shafts 95 11 have their end portions journaled in these brackets said shafts carrying spools 12 on which is wound the name bearing web or ribbon 13 of the device, said ribbon thus extending vertically through the 100 central portion of the casing between the spools. To provide for exposure of this ribbon at both sides of the casing, whereby the device may be placed in the center of the vehicle, the intermediate portions of the side 105 walls 8 and 9 are inset and provided with opposed sight windows 14 between which the ribbon is movable, the side wall portions being convergently inclined in forming the inset windows whereby to afford a wide range 110 of visibility of the windows and it is further noted that the windows are spaced apart only

a sufficient distance to permit movement of the web therebetween. A pair of horizontally alined drive and driven shafts 15 and 16 respectively, are disposed in the casing 5 above the sight windows, said shafts being journaled in the bearing brackets 10. These shafts carry feed rollers 17 which may be formed of rubber or other similar material to afford an effective frictional grip on the 10 ribbon as it moves therebetween to procure a positive and accurate feeding movement of the ribbon in moving therebetween, said rollers also serving to center the ribbon for movement between the windows. A guide 15 enlargement 18 is formed on one of the side walls below the sight windows and has its surface rounded for engagement by the ribbon.

Thus, rotative step movements of one of 20 the shafts 15 and 16 will procure progressive feeding movements of the ribbon past the sight windows 14 to thus expose successive street and station names, and it may at this point be stated that other matter may be 25 exposed through the window with the street name, or that the device may be used solely for advertising purposes to display successive symbols or legends.

To procure in the present embodiment of 30 our invention progressive feeding movements of the ribbon in either direction, intermeshing gears 19 are formed on the ends of the shafts 15 and 16, an armature carrying rock arms 20 and 21 are loosely mounted on 35 the end of the shaft 15, electromagnets 22 and 23 being mounted respectively above and below these arms, the arm 20, which is normally upwardly inclined being held away from its magnet by a contractile spring 24 secured to 40 the arm and the casing while the arm 21 is held away from its magnet by gravity, movement of both arms away from the magnet being limited by stops 25. The gear teeth of the gear wheels of the shaft 15 have a 45 series of ratchet teeth 26 formed thereon and each series of ratchet teeth is movable by a spring urged dog 27 slidably mounted in the corresponding armature rock arm and the inner end of each of these dogs is preferably 50 beveled to correspond to the taper of one side of each ratchet projection 26. The dog is held against rotation in the arm by pin and slot connection 28 therewith. An expansile 55 spring 29 is coiled on the outer portion of each dog and bears against a shoulder formed on the dog and against a stop plate 30 carried by the hub collar of the rock arm, each dog being provided with a head 31 at its outer end whereby the dog may be retracted 60 to permit manual adjustment of the position of the ribbon. Inasmuch as the series of ratchet projections 26 are beveled in opposite directions, successive energizations of the magnet 22 will procure feeding movements 65 of the ribbon in one direction while suc-

cessive energizations of the magnet 23 will feed the ribbon in the opposite direction. Actuation of the device is thus procured by completing electric circuits selectively through the magnets, and inasmuch as these 70 electric circuits may be completed by any one of a plurality of well known means, such as by engagement of vehicle carried contact members with circuit closers disposed along the track way or cable way, no specific circuit closing means is shown in the present instance since such means does not form a material part of our invention and may be supplied in any manner from the existing art. It will thus be seen that owing to the 75 fact the ratchet wheels and dogs operate in opposite direction when the said dog, which is idly associated with this ratchet, will act as a means for preventing a back lash of the drive shaft, and hence the tendency of the 80 ribbon to buckle when moved in either direction is overcome. The said dogs in other words perform a double function.

Proper winding and unwinding movements of the web on the spools 12 is insured 85 by friction belts 32 which are trained about small pulleys 33 on the ends of the spool shafts 11 and relatively large pulleys 34 on the feed roll shaft 16, the large pulleys 34 being substantially equal in diameter to the 90 diameter of the feed rollers 17, while the small pulleys are equal in diameter substantially to the diameter of the core portions of the ribbon spools 11. Each of the spools may thus be rotated to wind the ribbon thereon, and as the diameter of the wound ribbon is increased, the belt 32 will slip on the pulley 33 in idle movement.

An exceedingly simple and efficient device has thus been provided which will accurately 105 indicate the various streets or stations along the route of a railway vehicle, and the device is preferably set so that it is actuated immediately upon leaving one street or station to 110 display the name of the succeeding street or station, thus relieving the conductor or other person in charge from the work of announcing the various stations, as well as affording 115 an unmistakable clear indication in contrast to the usual oral announcement of the stations.

While we have shown and described a preferred embodiment of our invention it will be appreciated that various changes and modification of structure may be employed to 120 meet differing conditions of use and manufacture without departing in any manner from the spirit of our invention. For instance modified magnet control mechanism may be employed as shown in Figs. 6 and 7. 125 to lessen the necessary degree of movement of the armature in procuring the feeding impulses for the ribbon. In Fig. 6, each end of the feed roller drive shaft 15 carries a gear pinion 35 meshing with a gear 36 carried on a 130

stud shaft 37 journaled in the casing, said gear wheel 36 being provided with ratchet enlargements 26^a similar to the afore described ratchet enlargements 26 and engageable by the dog of the armature rock arm 20. In Fig. 7, this rock arm 20 is eliminated and a disk 38 is loosely mounted on the shaft 15 and carries a ratchet engaging dog 31^a. An angle lever has its angle portion pivoted on a stud 40 below and immediately adjacent the disk 38, this angle lever constituting a relatively long arm upstanding at one side of the disk and connected by a link 41 with a peripheral portion of the disk remote from the upper end of the link arm, the link lying slightly to one side of the center of the disk. The short arm of the angle lever is connected by a pivot link 42 with an armature plate 43 slidably mounted on pins 44 upstanding from a magnet 22^a. A very slight movement of the armature plate 43 will thus procure an adequate rotative step movement of the shaft 15 to properly feed the ribbon. The disk 38 is normally urged in a reverse direction of movement of a contractile spring 45 secured thereto and to the casing wall 8.

As shown in Fig. 8 each of the ribbon winding spools 34 is provided with a recess 46 in its bearing aperture which is adapted to receive a spring urged pawl 47 slidable in a transverse bore 48 of the shaft 16 to procure rotation of the pulley with the shaft in one direction of movement and permit the pulley to be stationary in the other direction of movement of the shaft, the recesses of the pulleys being inclined in opposed directions whereby only one of the pulleys 32 is driven at one time, to procure winding of the ribbon on the respective spool shaft 11.

40 We claim:

1. An indicator device of the class described comprising a casing, upper and lower ribbon carrying spools journaled therein, a ribbon carried by the spools and adapted to be selectively wound upon one or the other of the same, a drive shaft and a driven shaft journaled intermediate of the spools, feed rollers secured thereto and engageable with the opposite faces of the ribbon, an endless belt drive connection between the upper spool and drive shaft and between the lower spool and drive shaft, companion sets of

meshed gear wheels secured to the outer ends of the drive and driven shafts respectively, oppositely inclined tooth ratchet wheels carried by the gear wheels of the drive shaft whereby the same may be rotated in selective directions and an oscillatory member loosely mounted upon each end of the drive shaft, a pawl carried by each member engageable with the ratchet teeth of the juxtaposed gear wheel and means for positively actuating each oscillatory member, whereby the drive wheel may be selectively rotated in the desired direction to impart positive feed to the pair of feed rollers and to the pair of ribbon spools.

2. An indicator device of the class described comprising a casing, upper and lower ribbon carrying spools journaled therein, a ribbon carried by the spools and adapted to be selectively wound upon one or the other of the same, a drive shaft and a driven shaft journaled intermediate of the spools, feed rollers secured thereto and engageable with the opposite faces of the ribbon, an endless belt drive connection between the upper spool and drive shaft and between the lower spool and drive shaft, companion sets of meshed gear wheels secured to the outer ends of the drive and driven shafts respectively, oppositely inclined tooth ratchet wheels carried by the gear wheels of the drive shaft, whereby the same may be rotated in selective directions and an oscillatory member loosely mounted upon each end of the drive shaft, a bell-crank lever mounted in the casing in juxtaposition to each oscillatory member, the bell-crank lever being provided with a short arm and a long arm, means connecting the long arm of the bell-crank lever with the oscillatory member, a reciprocative armature in link connection with the short arm of each bell-crank lever and an electromagnet for actuating each armature, whereby motion is selectively imparted to the pair of feed rollers and pair of ribbon spools.

In testimony that we claim the foregoing we have hereunto set our hands at Racine, in the county of Racine and State of Wisconsin.

ALONZO F. GAIDOS.
FRANK H. GUY.
